AMULET

Lawrence E. Cooke, Roslyn Heights, N. Y.

Application October 14, 1950, Serial No. 12,564

Term of patent 3½ years

(Cl. D45—17)

To all whom it may concern:

Be it known that I, Lawrence E. Cooke, a citizen of the United States, residing at Roslyn Heights, county of Nassau, and State of New York, have invented a new, original, and ornamental Design for an Amulet, of which the following is a specification; reference being had to the accompanying drawing, forming part thereof.

In the drawing,

Fig. 1 is a front elevational view of an amulet, embodying my new design, and

Fig. 2 is a side elevational view thereof.

I claim:

The ornamental design for an amulet, substantially as shown.

LAWRENCE E. COOKE.
